UNITED STATES PATENT OFFICE.

JOHN GOOD, OF NEW YORK, N. Y.

LABYRINTH-VALVE.

1,189,940.

Specification of Letters Patent. Patented July 4, 1916.

Application filed January 17, 1914. Serial No. 812,633.

To all whom it may concern:

Be it known that I, JOHN GOOD, a citizen of the United States, residing in the borough of Brooklyn, city, county, and State of New York, have invented the following described Improvements in Labyrinth-Valves.

The invention consists in an improved formation of the lamellæ or valve members, promoting compactness of assemblage and increasing the efficiency and also eliminating the tendency to warp, whereby the said valves are particularly useful in internal combustion engines and other places where subject to high temperatures, it being understood however that the said valves are susceptible of use in any relation where fluid pressures are to be controlled.

In the accompanying drawings Figure 1 is a central vertical section through the cylinder head of an internal combustion engine provided with valve mechanism in accordance with this invention. Fig. 2 is a section on line II-II, with the cover-plate removed. Figs. 3, 4, 5 and 6, are modified forms susceptible of use in the structure of Figs. 1 and 2.

In Fig. 1 the valve mechanism is contained in a cylinder head structure 1, which is water-jacketed and provided with an exhaust passage 2 and an intake passage 3. The intake and exhaust valves for these passages may be of identical structure, if desired, but in the present case they are shown slightly different, as a convenient means of illustrating modifications of the invention. Both are driven by a common operating member, such as the valve shaft 4, which shaft may be mounted either horizontally as shown, or in any other suitable position according to the design of the particular engine or device in which used. This shaft is driven in proper phase with the engine, either on quarter or half time, by means of a skew gear 5 secured to one end and driven by a complementary gear 6 on a drive shaft 7.

If the engine is a multi-cylinder engine, the shaft 4 is placed crosswise on the row of cylinders and the drive shaft 7 is common to all of the valve shafts driving each in its proper phase. The labyrinth valves are composed of two series of lamellæ, those of one series interlapping with those of the other without contact and so as to form a labyrinth crevice between them, and the two series being relatively movable so that their

respective openings can be brought into and out of alignment with each other and with the intake (or exhaust) passage.

Referring first to the exhaust valve, the series of lamellæ marked 8, is fixed in position in the head structure with the port opening 8^a thereof in permanent alignment with each other and the passage 2. These members have the form of dished annular plates or disks, most conveniently segments 60 of spheres, as indicated, and are two in number in the present case, although they may be of any desired number dependent upon the dimensions of the labyrinth crevice and the fluid pressure to be controlled. Ordinarily more than two will be required for combustion engines. Each fixed member in the exhaust valve has a flat annular rim by means of which it is clamped and keyed in place between the series of interposed rings 65 9, which space them from each other and from the ends of their housings. The members marked 10 of the complementary series are fixed to the shaft 4, being clamped thereon by means of the nuts 11, with a series of washers 12 interposed between them, and their openings 10^a are set in alignment with each other. These movable members are of 70 similar form to the fixed members so that the narrow labyrinth crevice between the 75 two series is of substantially uniform width. Through this crevice the fluid under pressure within the engine must travel in order to escape, but when the valve shaft carrying the movable members is rotating, the 80 thin film of fluid tending to force its way through the crevice, and adhering more or less to the surface of the lamellæ, encounters such degree of surface friction and is so deflected or dragged from the shortest path 85 by the rotation of the surfaces, that any escape is effectually prevented, although a free passage is opened through the valve each time the openings 8^a and 10^a come in 90 registry.

The head structure 1 conforms to the dished formation of the valve members, as does also the cover plate 13, which clamps the fixed members 8 and their spacer rings 9 in place, the faces of the head structure 105 casting and its cover plate also serving to form part of the labyrinth crevice referred to. One of the journal seats for the shaft 4 is provided in the cover plate 13, which also forms part of the casing for the skew gears 110

5 and 6 above referred to. The other end of the valve shaft 4 is journaled in the complementary cover plate 14 of the intake valve. This cover is applied to the intake valve in like manner for clamping the fixed lamellæ of that valve in position. The shaft bearing 15 therein is formed with a hub portion exteriorly threaded to receive an adjustable sleeve 16, the latter being externally threaded to receive an outer sleeve or housing 17, both sleeves being provided with set screws to lock them in position. The end of the valve shaft carries a collar 18 fixed thereon by a nut and held or confined to rotate between the proximate faces of the two sleeves. By this means the endwise position of the shaft 4 may be initially adjusted to set the rotary lamellæ in a centralized position between the fixed lamellæ and when the bearing surfaces have become worn to an extent likely to permit the two series of lamellæ to come into frictional or binding contact these sleeves may be manipulated in an obvious manner to restore the original condition. Between the valves, the shaft 4 is incased in the water-jacket of the head structure but such jacket is not essential at this point and can be omitted if desired.

The intake valve differs from the exhaust valve merely in that the fixed lamellæ 19 thereof have no flat rims upon their outer margins but are curved from center to circumference and the spacer-rings 20 are correspondingly curved. The inner margins of the rotary lamellæ 21 are also curved instead of straight, as are also their spacer washers 22. Otherwise the construction is identical. In both intake and exhaust valves however, the path of escape for the fluid is formed between inclined surfaces and because of such fact is longer than would otherwise be the case if the lamellæ were flat disks of the same diameter, as shown for example in corresponding application filed by me June 28, 1913, and in both cases the lamellæ are stiffer in proportion to their thickness by reason of the dished shape and are also less likely to warp under the effect of heat.

In the form illustrated by Figs. 3 to 6, a similar extension or elongation of the path of escape crevice is provided by the inclination of the surfaces of opposite lamellæ, and in Figs. 4, 5 and 6 a still further increase of length and obstruction to flow is provided by introducing an angle in the inclined portions, giving the crevice a zigzag radial section. All of these forms can be substituted for the spherical forms of Figs. 1 and 2. The angles of the zigzag occur near the centers of the lamellæ and also near their circumferences and outside of the boundary of the port openings, in which position they are most useful, since it is in the neighborhood of the openings that the path of escape crevice is shortest. By introducing the angles in

such locations, the crevice between the proximate faces of adjacent lamellæ is rendered tortuous or curved, thus by so much increasing the labyrinthic character of the valve as a whole, and without unduly enlarging its size. The extended length of the crevice beyond the port opening by means of the inclination of the crevice surfaces, whether a single inclination or curve as in Figs. 1 and 3, or a double or multiple inclination such as shown in Figs. 4 to 6, thus constitutes an important feature of the present invention irrespective of the remaining construction of the valve, and the means of obtaining such extension are broadly claimed herein.

In Fig. 3 the fixed lamellæ 19¹ and rotary lamellæ 21¹ are spaced by rings 20¹ and washers 22¹, all of which are of conical form and it will be understood that this form of valve can be incorporated in the engine or other apparatus after the manner shown in Fig. 1, or otherwise, in an obvious manner.

In Fig. 4 the fixed lamellæ 23 are centrally dished to form the double angles 24, and then again dished near their circumference to form the double angles 25, the angles 24 and 25 being both disposed between the line port openings (23^a) and the inner and outer margins of the member, the intermediate portion in which the port opening is formed being in this form perpendicular to the axis of the valve.

In Fig. 5, the fixed lamellæ 26 have their angles 27 and 28 disposed in the same general relation but the intermediate portions in which the port openings are formed are disposed at an inclination to the axis of the valve.

In Fig. 6 the fixed lamellæ 29 have their angles 30 and 31 facing in the same direction, the intermediate portion in which the port openings are formed being in this case also radial to the axis of the valve. It will be evident that other forms of inclined and zigzag crevices having one or more angles between the boundaries of the port openings and the inner and outer circumferences of the lamellæ can be substituted for those above described. Angles can obviously also be formed in the ported parts of the crevice forming valve members if desired and any of the lamellæ shown can be stamped from sheet metal stock.

Where both valves are opposed or on the same shaft, as in Fig. 1, they can be mounted with their dished sides facing away from each other, thereby permitting the valves to be brought closely together, and also permitting an increased number of lamellæ or an increase in the thickness of each, without unduly extending the length of the valve shaft. This arrangement of the valves will provide a smaller clearance space when used in internal combustion engines, and of course the reversal of such arrangement will

provide an apparent effect. Between the valves, when thus arranged, at one side of the valve shaft in Fig. 1, a hole is provided to receive a spark plug 33, pet-cock, fuel injector or other device, as the case may be.

In Fig. 1 I have shown the members 10 and 21 with a general tapered section, which further promotes compactness and freedom from warping. The fixed members 8 and 19 are formed to fit in the spaces between the rotary members.

Having now fully described the invention, I claim the following:

1. A labyrinth valve comprising interlapping lamellæ having port openings adapted to form a free passage through the valve when in alinement and provided with inclined portions beyond the boundaries of the port openings forming a labyrinth crevice.

2. A labyrinth valve comprising interlapping lamellæ provided with port openings adapted to open a free passage through the valve when said openings are in alinement and provided with angular juxtaposed surfaces beyond the boundaries of said port openings forming a tortuous crevice between lamellæ.

3. A labyrinth valve comprising a series of dished members and a series of similarly dished members, the members of one series interlapping without contact with those of the other series and each provided with port openings adapted to be brought into alinement with port openings in the other members.

4. A labyrinth valve comprising a series of dished lamellæ and a series of similarly dished lamellæ interlapping therewith, both series provided with port openings which form a free passage through the valve when in alinement and being related and assembled to form a labyrinthic crevice between them.

45 5. Valve mechanism for engines and like purposes comprising a valve shaft, a pair of labyrinth valves thereon each formed of

series of interlapping, dished, lamellæ, their dished sides facing in opposite directions.

6. A valve mechanism for gas engines and like uses, comprising a pair of labyrinth valves each formed of series of interlapping dished lamellæ having their dished sides faced away from each other.

7. A labyrinth valve comprising a series of fixed lamellæ and a series of rotary lamellæ interlapping therewith, each provided with port openings adapted to be brought into alinement to open a free passage through the valve and both series of lamellæ having a cross section forming angles on the proximate faces thereof.

8. A labyrinth valve comprising lamellæ interlapping without contact, having port openings adapted to form a free passage through the valve when in alinement, and provided with double inclined portions beyond the boundaries of the port openings forming a tortuous crevice.

9. A labyrinth valve comprising interlapping but non-contacting lamellæ provided with port openings adapted to form a free passage through the valve when said openings are in alinement and provided with juxtaposed surfaces forming a narrow crevice between lamellæ, the said juxtaposed surfaces being complementarily shaped to form angles in the portions of said crevice between the edges of the lamellæ and the boundaries of the port opening.

10. A labyrinth valve comprising a series of fixed lamellæ and a series of rotary lamellæ, each provided with port openings adapted to be brought into alinement to open a free passage through the valve and both series of lamellæ formed of zigzag cross section.

In testimony whereof, I have signed this specification in the presence of two witnesses.

JOHN GOOD.
